UNITED STATES PATENT OFFICE.

ERASTUS WOODWARD, OF SOMERVILLE, ASSIGNOR TO GEORGE W. COPELAND, OF MALDEN, MASSACHUSETTS.

FASTENING-DRIVING MACHINE.

SPECIFICATION forming part of Letters Patent No. 251,756, dated January 3, 1882.

Application filed November 16, 1881. (No model.)

To all whom it may concern:

Be it known that I, ERASTUS WOODWARD, of Somerville, in the county of Middlesex and State of Massachusetts, a citizen of the United States, have invented a certain new and useful Improvement in Fastening-Driving Machines, of which the following is a full, clear, and exact description, reference being had to the accompanying drawings, forming part of this specification in explaining its nature, in which—

Figure 1 is a side elevation of my machine. Fig. 2 is an elevation of a portion thereof upon the opposite side from that shown in Fig. 1. Fig. 3 is a plan of a part of the treadle mechanism.

This invention is an improvement upon those described in Letters Patent No. 246,437, granted me August 30, 1881, for improvement in tacking-machines, and Patent No. 248,544 for lasting and fastening machine, dated October 18, 1881. In the last-named patent I have described a fastening-driving machine so organized that the act of presenting the work to the fastening-driving machine in proper position to receive the fastening automatically starts and stops the machine, and that the parts automatically resume their original position. In lieu, however, of starting and stopping the fastening-driving machine by the work, I herein describe a modified form of construction which I consider in its broad features to be covered in said last-named application, but which, being somewhat different in construction, is entitled to specific protection. It consists of the use of a foot-treadle and intermediate mechanism for operating the start and stop mechanism of the fastening-driving machine in addition to the foot-treadle for operating the jack in the manner described in said application. In all other respects the mechanism is like that described in said patents, with the exception that the braking or friction device described in another pending

application filed September 27, 1881, is also 45 used.

A is the treadle for operating the jack A'. B is the fastening-driving machine. B' is its nozzle. C is a yielding guide. D is the treadle for operating the start and stop motions. D' 50 is an arm which in part is the equivalent of the lever d⁶ of said Patent 246,437. It has at its end the latch d, (the equivalent of the latch d¹² of said patent,) which engages with the pin d' on the lever d², which lever is the 55 same as the lever d² of the patent. A connecting-rod, d³, connects the end of the treadle D with the latch-arm. As the treadle is pivoted at d⁴ it follows that upon the downward movement of its front end its rear end is lifted, 60 thereby lifting the latch-arm, dropping the latch, and permitting the movable member of the clutch to engage with the fixed member, as described in said patent. Then by gravity the latch falls upon the pin and is operated by 65 the cam to unship the clutch, as indicated in the patent.

In operating the machine the operator controls the movement of the jack by one treadle and the actuation of the start and stop motions by the other treadle.

Having thus fully described my invention, I claim and desire to secure by Letters Patent of the United States—

The combination of the nozzle of a fastening-driving machine, a jack and last adapted to be raised to and held against the said nozzle by a treadle while the fastening is driven, and a second treadle adapted to actuate the start and stop motions of the fastening-driving machine while the jack-treadle is kept down to hold the last and jack to the nozzle, substantially as specified.

ERASTUS WOODWARD.
